US00D808382S

(12) **United States Design Patent** (10) **Patent No.:** **US D808,382 S**
(45) **Date of Patent:** **** Jan. 23, 2018**

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/563,876**

(22) Filed: **May 9, 2016**

Related U.S. Application Data

(63) Continuation of application No. 29/541,441, filed on Oct. 2, 2015, now Pat. No. Des. 767,560, which is a continuation of application No. 29/471,181, filed on Oct. 29, 2013, now Pat. No. Des. 744,474, which is a continuation of application No. 29/457,349, filed on Jun. 9, 2013, now Pat. No. Des. 694,746.

(57) **CLAIM**

The ornamental design for electronic device, as shown and described.

DESCRIPTION

FIG. 1 is a front, top perspective view of an electronic device showing our new design;

FIG. 2 is a bottom, rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate structure or features which form no part of the claimed design.

1 Claim, 7 Drawing Sheets
